(57) **CLAIM**

(**) Term: **14 Years**

The ornamental design for oblong shaped lamp openings for use in a vehicle bumper assembly, as shown and described.

(21) Appl. No.: **29/170,421**

DESCRIPTION

(22) Filed: **Nov. 6, 2002**

FIG. 1 is a perspective view of oblong shaped lamp openings for use in a vehicle bumper assembly showing my new design;

(51) LOC (7) Cl. **26-99**

FIG. 2 is a front elevational view thereof;

(52) U.S. Cl. **D26/139**

FIG. 3 is an enlarged, partial front elevational view of a first embodiment of the oblong shaped lamp openings for use in a vehicle bumper assembly;

(58) Field of Search D26/28-36, 120,
D26/139; 362/61, 80, 81, 82, 83, 326, 329-340

FIG. 4 is a first sectional view taken along line 4—4 of FIG. 3;

(56) **References Cited**

FIG. 5 is a second sectional view taken along line 5—5 of FIG. 3;

U.S. PATENT DOCUMENTS

FIG. 6 is an enlarged, partial front elevational view of a second embodiment of the oblong shaped lamp openings for use in a vehicle bumper assembly;
